UNITED STATES PATENT OFFICE.

MABEL W. WILLSON AND ANDREW E. WILLSON, OF GRAND RAPIDS, MICHIGAN.

POWDER PUFF.

1,423,745.

Specification of Letters Patent. Patented July 25, 1922.

Application filed October 18, 1921. Serial No. 508,554.

To all whom it may concern:

Be it known that we, MABEL W. WILLSON and ANDREW E. WILLSON, citizens of the United States, residing at Grand Rapids, in 5 the county of Kent and State of Michigan, have invented certain new and useful Improvements in Powder Puffs, of which the following is a specification.

Our invention relates to improvements in 10 powder puffs for use as a toilet article upon the face and neck of ladies, and its objects are: first, to provide a powder puff that may be used both for distributing and blending powder and rouge upon the face from the 15 same puff; second, to provide a powder puff that may be made to so protect the powder and rouge as to keep it practically antiseptic and free from dust and foreign matter when not in actual use for toilet purposes; 20 third, to provide a means whereby the powder and rouge will be confined, when the puff is being carried, so as to avert all danger of smearing other articles that may be in a hand bag, or other place, with the puff, and, 25 fourth, to provide a powder puff with which only the surface containing the powder that it is desired to place upon the cheek or neck of the user need be exposed while using the puff, the other wings of the puff being locked 30 securely together.

We attain these objects by the construction and arrangements of parts shown in the accompanying drawing, in which Fig. 1 is a plan of the puff closed in position for storing 35 and carrying without danger of smearing other articles with the powders. Fig. 2 is a perspective of the puff showing one side open ready for placing the powder upon the cheek. Fig. 3 shows the puff closed and the 40 several wings securely fastened together at the edges. Fig. 4 is an edge view of the powder carrying elements showing how they are connected to form a hinge connection between them, and, Fig. 5 is an elevation of 45 the puff with one pair of folds open, and the other pair of folds closed, showing the position and condition of the puff when opened for use, the folded wings forming a handle with which to properly handle the puff.

50 Similar reference numerals indicate similar parts throughout the several views.

This powder puff is made up of several elements, as follows: First, we have the moisture proof covering indicated at 1 in 55 Fig. 1, which is placed outside of, or over the soft, fluffy powder carrying element 5.

This powder carrying element is made from a very soft velvet, plush, or cotton flannel of such a texture that the folded surfaces, as at 2, may be stitched together to form the folds 60 of the puff, without marring either powder surface. In other words, so that when the surfaces 5 are exposed there will be no impression of a seam at the line of stitching, and no obstruction to the free use of the 65 powder upon the surface at 5'.

When in use we open but one pair of wings, as indicated in Figs. 2 and 5, the other pair of wings being appropriated as a handle or hand hold with which to manipulate 70 the puff when powdering the cheeks, &c. When not in use the wings are folded together, as in Figs. 3 and 4, and as indicated in Fig. 1, and may be securely connected at the edges by the use of straps 3 stitched 75 to one pair of wings, as at 3', and the other end temporarily secured to the other wing by means of the clasps 4, 4', or other available means, so as to absolutely confine the 80 powder and avert the danger of the powdered surfaces becoming contaminated with any form of foreign matter.

When preparing to use this puff one or the other of the straps 3 is disconnected from the opposite wing and the wings are swung 85 into the position indicated by the dotted lines in Fig. 3. If the upper wings are opened the part 6 will be appropriated as a handle, and if the lower wings are swung open, the upper wings, as 1, will be utilized 90 for the purpose, the opening and closing of said wings are indicated by the positions of the arrows in Figs. 3 and 5. It will be understood that with this puff it will be necessary for a lady to carry but one puff for two 95 colors of powder, and when the puff is not in use there need be no possibility of the powder becoming contaminated or unsanitary, or rendering other articles dusty and unsanitary or unsightly from contact with 100 the powder on the puff.

Having thus fully described our invention, what we claim as new in the art, is:

1. In a powder puff, two pieces of fabric each having one plain surface and one fluffy 105 surface, each of said pieces of fabric centrally folded with the plain surfaces outward and the folded edges stitched together in such a manner that the puff may be folded with both pairs of fluffy surfaces contacting 110 and protected, or may be opened so one pair of said surfaces may be exposed and made

to form a fluffy surface for the storage and application of powder.

2. In combination with the elements covered in claim 1, a moisture proof covering placed over the outer surfaces of the fluffy material.

3. In combination with the elements covered in claim 1, a moisture proof covering for the outer surfaces, and appropriate securing elements for securing the puff with the fluffy surfaces contacting.

4. In combination with the elements covered in claim 1, securing means attached to

the edges of the puff in positions to securely connect the pairs of fabric in place with the 15 fluffy surfaces in contact.

5. In combination with the elements covered in claim 1, a strap secured to each of two wings, and a button upon each of the two opposite wings arranged to securely fasten the free edges of said pairs of wings together. 20

Signed at Grand Rapids, Michigan, October 8, 1921.

MABEL W. WILLSON.
